UNITED STATES PATENT OFFICE.

LARS LARSON, OF CHICAGO, ILLINOIS.

SLAG-DISINTEGRATING APPARATUS.

1,103,886.

Specification of Letters Patent. Patented July 14, 1914.

Application filed December 12, 1913. Serial No. 806,204.

To all whom it may concern:

Be it known that I, LARS LARSON, a citizen of the United States, and a resident of the city of Chicago, county of Cook, and 5 State of Illinois, have invented certain new and useful Improvements in Slag-Disintegrating Apparatus, of which the following is a specification.

My invention relates to improvements in 10 apparatus for disintegrating slag such as accumulates in smelting furnaces when in operation.

The object of my invention is the production of slag disintegrating apparatus as 15 mentioned which will be of improved construction, apparatus in which the necessity of dampening or subjecting the same directly to the action of cold water in order to cool the same will be obviated, and further apparatus which will be of durable and 20 economical construction and efficient in operation.

Other objects will appear hereinafter.

The invention consists in the combinations and arrangements of parts hereinafter described and claimed.

The invention will be best understood by reference to the accompanying drawings forming a part of this specification, and in 30 which—

Figure 1 is a side elevation, partly in section of a slag disintegrating apparatus embodying my invention, Fig. 2 is a partially sectional end elevation thereof, Fig. 3 is a 35 section taken on substantially line $x-x$ of Fig. 2, Fig. 4 is a section taken on substantially line $y-y$ of Fig. 1, Fig. 5 is an enlarged fragmentary detail section taken on substantially line $z-z$ of Fig. 3, and Figs. 40 6 and 7 are perspective views of the scraping and removing devices employed in conjunction with the cooling trough of the apparatus for removing the slag therefrom.

In the preferred form of construction as 45 illustrated in the drawings, I have illustrated the base of a conventional cupola or smelting furnace 1. Leading from the furnace 1 is the usual slag conduit 2 which is adapted to convey the slag drawn from the 50 furnace and deposit the same into a reservoir 3, the latter, in practice, being of comparatively large dimensions in order to adapt the same to serve as a sort of storage receptacle or chamber preparatory to run-

ning the same off into the cooling and dis- 55 integrating apparatus hereinafter described.

Leading from the reservoir 3 is a conduit 4 which communicates with an elongated trough 5 which is provided preferably with a metallic lining 6 as clearly shown in 60 Fig. 4. Arranged adjacent to and extending parallel with the trough 5 is a second trough 7 separated from the former by a common wall 8. Communication between the troughs 5 and 7 is established through 65 transversely extending openings or passages 9 in the wall 8 adjacent the bottom thereof. The openings 9 are arranged in sets, each set 70 consisting of a plurality of said perforations which are of graduated dimensions or diameters as clearly shown in Fig. 3. These openings are controlled by an elongated plate or slide valve 10, the longitudinal edges of 75 which are suitably mounted in guides provided at the side of the wall 8 registering with trough 5. The plate 10 is provided with spaced perforations 11 one of which cooperates with each set of openings 9. The arrangement is such, as will be observed, 80 that through sliding adjustment of said plate 10 each opening 11 may be brought into registration with any one of the corresponding openings 9 in order to permit of the passage of the molten slag from the trough 5 to the trough 7. By providing a 85 plurality of openings 9 of graduated sizes the flow of molten slag from the trough 5 to the trough 7 may be regulated, it being clear that when the openings 11 are in registration with the smallest openings 9 a comparatively small amount of slag will be permitted to flow from one trough to the other, the amount which is permitted to flow from one trough to the other being increased as 90 the plate 10 is moved into registration with the succeeding openings 9. The regulation of the flow of molten slag from one trough to the other is of importance since the condition of the slag both as to its temperature and consistency continually varies, such variation necessarily affecting the mobility thereof. This sliding adjustment of the plate 10 is effected by means of an exteriorly projecting stem 12 provided at one 100 end thereof upon which is threaded a hand wheel 13 which is held against longitudinal movement in a bracket 14, the arrangement being such that longitudinal movement of

the plate will be secured upon rotation of said hand wheel.

The bottom 15 of the trough 7 is longitudinally corrugated as clearly shown in Fig. 4 and formed under said bottom is a chamber 16 adapted to permit of the circulation of cold water introduced into said chamber through a pipe 17 at one end thereof and discharged from said chamber through a drain pipe 18 provided at the other end of said chamber. With this arrangement, when the apparatus is in use, the bottom 15 of trough 7 will be maintained continually in a cold condition so as to effect cooling of the slag which is introduced into said trough from the trough 5. By corrugating the bottom of the trough 7 the cooling surface with which the molten slag is brought into contact is increased thereby increasing the efficiency of the cooling process.

The removal of the slag from the trough 7 after cooling and hence hardening thereof is effected by means of members 19 and 20 which are arranged in said trough for longitudinal movement therein. The member 20 is of rectangular form being of a height and width adapting the same to be snugly received in the trough 7. The front and bottom of each of the members 20 are open, the remaining sides thereof being closed. Arranged within each member 20 is an obliquely disposed blade 22 rigidly secured in position as by riveting. The blade 22 is so arranged that the forward end thereof will be positioned adjacent the side of the trough provided with the inlet openings 9, said blade being adapted, upon longitudinal movement of the member 20 to operate in the manner of a plow to effect a uniform distribution of the slag over the bottom of the trough. Without this arrangement the slag might accumulate at the side of the trough adjacent the entrance openings 9, and therefore result in over-taxing the corresponding sides of the scraping and removing devices. The blades 22 are of a width less than the height of the buckets 20 so that if the slag accumulates in front of the same in too large quantities, it may pass over the upper edges of said blades and be caught up in the rearward ends of the members 20 as will be readily understood. The rear wall of each of the members 20 at its lower edge 23 is preferably bent forwardly, as clearly shown in Fig. 6 in order to adapt the same to more effectually scrape the bottom of the trough 7 in the operation of said members 20 in said trough, the edges 23, as well as the lower edges of the blades 22 traveling in close proximity with the crests of the corrugations of the bottom 15 in the operation of the apparatus.

The members 19 are rectangular in form but are spaced above the bottom 15 as clearly

shown in Fig. 1. Each of the members 19 is closed at all of its sides except the front. The bottom of each of the members 19 at the front end is provided with a downwardly inclined extension 21' to which are rigidly secured the rearward ends of inclined scraper fingers 21 so spaced as to be adapted to engage in the grooves or recesses of the corrugations of the bottom 15 in the movement of members 19 in trough 7. Said fingers 21 are thus adapted, in the operation of the apparatus, to effectually remove the slag from the grooves or recesses of the corrugations of bottom 15, the slag which is thus removed being adapted to travel upwardly on said fingers and over the extension 21' and be collected in the members 19 as will be readily understood.

The members 19 and 20 are carried by two spaced endless sprocket chains 24 which travel around sprocket wheels 25 suitably mounted at the respective ends of the trough 7, said sprocket chains being preferably provided at the joints therein with rollers adapted to ride upon the upper edges of the longitudinal walls of trough 7 as clearly shown in Figs. 1 and 2. The members 19 and 20 are rigidly secured to the chains 24 by means of transversely extending bars 26 which project through perforations provided in the lateral walls of said members as clearly shown in Figs. 6 and 7. Also co-operating with the members 19 and 20 are reinforcing rails 27 and 27' arranged in spaced pairs, there being one pair arranged above the trough 7 and one pair arranged below said trough as clearly shown in Fig. 1. Provided upon the upper side of each of the members 19 and 20 is a pair of spaced rollers 28 adapted to contact with the under side of rails 27, when said members are in operative position in the trough 7 and adapted to engage against the upper sides of rails 27' when said members are inoperative and traveling under said trough as shown in Fig. 1. Contacting with the opposite sides of said rails are rollers 29 carried in bearing housings 30 adjustably secured by nuts 31 to the outer ends of posts 32 which project perpendicular from the corresponding sides of the members 19 and 20. The arrangement is such, as will be observed, that the members 19 and 20 will be securely held against tilting movement in a vertical plane extending longitudinally of the trough, the rails 27 serving to counteract the strain upon said members 19 incident to the scraping and slag removing operation. The rails 27' serve simply to prevent sagging of the under sides of the chains in the movement of the members 19 and 20 under the trough. Through the adjustment which is afforded through rotation of nuts 31, any lost motion may be taken up and the rollers 28 and 29 held in

close contact with the opposite sides of the rails.

The opposite ends of the trough 7 are open permitting of entry of the members 19 and 20 at one end thereof and exit of said members from the other end of said trough. As the members 20 reach the last mentioned end of the trough and register with the corresponding sprocket wheels 25, said members will be tilted to dumping positions so as to effect discharge of the contents thereof into a disintegrating or crushing device 33 arranged below the dumping point of said members as clearly shown in Fig. 1. The crushing or disintegrating device 33 is of any approved design, and leading therefrom is an endless bucket conveyer or elevator which is adapted to convey the disintegrated slag passed through the device 33 and deposit the same into a storage chamber 35, from whence the disintegrated slag may be withdrawn as desired for use. The various parts of the apparatus set forth are supported by suitable frame work as shown so as to produce a firm and rigid construction. In the operation then of the apparatus the hot molten slag first flows from the furnace or cupola 1 through the conduit 2 into the reservoir 3. From said reservoir the hot molten slag flows through conduit 4 into the distributing trough 5, whence it is introduced through the openings 9 which are controlled by slide valve 10 into the cooling trough 7. The bottom of trough 7 being maintained in a cool condition through the circulation of cold water contacting with the under side thereof, the hot molten slag as the same is introduced into trough 7 will be cooled and therefore hardened by contact with said bottom. After cooling and hardening the slag will be removed from the trough 7 by the scraping and conveying devices 19 and 20 which will carry the slag in large non-uniform chunks or pieces toward one end of the trough and discharge the same into the disintegrating device 33, whence the same, after disintegration, will be deposited in a storage chamber 35 by the conveyer or elevator 34.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. Apparatus of the class described comprising a trough; means for admitting the material to be treated to said trough; means

arranged in the bottom of said trough for cooling the material admitted to said trough, said trough being longitudinally corrugated; and means for removing the contents of said trough, substantially as described.

2. Apparatus of the class described comprising a trough; means for admitting the material to be treated to said trough; means arranged in the bottom of said trough for cooling the material admitted to said trough, said trough being longitudinally corrugated; and means movable longitudinally of said trough for removing the contents thereof, substantially as described.

3. Apparatus of the class described comprising a trough; means for admitting the material to be treated to said trough; means for cooling the material admitted to said trough; and means mounted in said trough for longitudinal movement in one direction for removing the contents of said trough, substantially as described.

4. Apparatus of the class described comprising an elongated trough; means for admitting the material to be treated to said trough at various points along its length; means for cooling the material admitted to said trough; and means for removing the contents of said trough, substantially as described.

5. Apparatus of the class described comprising an elongated trough; means for admitting material to be treated to said trough at various points along its length and adjacent the bottom of said trough; means for cooling the material admitted to said trough; and means for removing the contents of said trough, substantially as described.

6. Apparatus of the class described comprising a trough open at both ends; means for admitting the material to be treated to said trough; means for cooling the material admitted to said trough; and means adapted to enter one end of said trough, travel longitudinally of the latter, and pass out through the opposite end of said trough, for removing the contents of the latter, substantially as described.

7. Apparatus of the class described comprising a trough; means for cooling the contents of said trough; and means for removing from said trough the contents thereof, said removing means comprising a bucket movable longitudinally of said trough, substantially as described.

8. Apparatus of the class described comprising a trough; means for cooling the bottom of said trough, said trough bottom being longitudinally corrugated; and means movable longitudinally of said trough and engaging in the grooves of the corrugations of said bottom for removing from said trough the contents thereof, substantially as described.

9. Apparatus of the class described com-

prising a trough; means for cooling the bottom of said trough, said trough bottom being longitudinally corrugated; means for removing from said trough the contents thereof, said removing means comprising a bucket movable longitudinally of said trough; and means at the front end of said bucket for engaging the grooves of the corrugations of said bottom, substantially as described.

10. Apparatus of the class described comprising a trough; means for cooling the bottom of said trough, said trough bottom being longitudinally corrugated; means for removing from said trough the contents thereof, said removing means comprising a bucket movable longitudinally of said trough; and fingers at the front end of said bucket for engaging the grooves of the corrugations of said bottom, substantially as described.

11. Apparatus of the class described comprising a trough; means for cooling the bottom of said trough, said trough bottom being longitudinally corrugated; means for removing from said trough the contents thereof, said removing means comprising a bucket movable longitudinally of said trough; and spaced forwardly inclined fingers at the front end of said bucket for engaging the grooves of the corrugations of said bottom, substantially as described.

12. Apparatus of the class described comprising a trough; means for cooling the contents of said trough; means for removing from said trough the contents thereof, said removing means comprising a plurality of buckets movable in said trough longitudinally thereof, certain of said buckets being open at their forward ends, the forward end of the bottom of each of the last mentioned buckets being inclined downwardly into close proximity with the bottom of the trough, substantially as described.

13. Apparatus of the class described comprising a trough; means for cooling the contents of said trough; means for removing the contents of said trough, said removing means comprising a plurality of scraper members adapted to travel through said trough longitudinally thereof; and an endless element carrying said scraper members, substantially as described.

14. Apparatus of the class described comprising a trough; means for cooling the contents of said trough; means for removing the contents of said trough, said removing means comprising a plurality of spaced buckets movable in said trough longitudinally thereof; and endless elements for moving said buckets in said trough, substantially as described.

15. Apparatus of the class described comprising a trough; means for cooling the contents of said trough; means for removing

the contents of said trough, said removing means comprising a plurality of spaced buckets movable in said trough longitudinally thereof; and endless chains carrying said buckets, substantially as described.

70

16. Apparatus of the class described comprising a trough; means for cooling the contents of said trough; means for removing the contents of said trough, said removing means comprising a plurality of spaced buckets movable in said trough longitudinally thereof; and endless chains carrying said buckets and passing around sprocket wheels provided at the ends of said trough, said buckets being so arranged upon said chains that the same will be dumped as they pass around said sprocket wheels, substantially as described.

80

17. Apparatus of the class described comprising a trough; means for cooling the contents of said trough; means for removing the contents of said trough, said removing means comprising a plurality of scraper members adapted to travel through said trough longitudinally thereof; an endless element carrying said scraper members; and reinforcing rails for guiding said scraper members, substantially as described.

90

18. Apparatus of the class described comprising a trough; means for cooling the contents of said trough; means for removing the contents of said trough, said removing means comprising a plurality of spaced buckets movable in said trough longitudinally thereof; endless chains carrying said buckets; and reinforcing rails for guiding said buckets, substantially as described.

95

19. Apparatus of the class described comprising a trough; means for cooling the contents of said trough; means for removing the contents of said trough, said removing means comprising a plurality of scraper members adapted to travel through said trough longitudinally thereof; an endless element carrying said scraper members; reinforcing guide rails for said scraper members; and means on said scraper members engaging against opposite sides of said rails for preventing tilting of said members in a vertical longitudinal plane relative to said rails, substantially as described.

110

20. Apparatus of the class described comprising a trough; means for cooling the contents of said trough; means for removing the contents of said trough, said removing means comprising a plurality of scraper and carrier members movable in said trough longitudinally thereof; endless chains carrying said members; reinforcing guide rails for said members; and means on said members engaging against opposite sides of said rails for preventing tilting of said members in a vertical longitudinal plane relative to said rails, substantially as described.

115

21. Apparatus of the class described com-

125

126

prising a trough; means for cooling the contents of said trough; means for removing the contents of said trough, said removing means comprising a plurality of scraper and carrier members movable in said trough longitudinally thereof; endless elements carrying said members; reinforcing guide rails for said members; and rollers on said members engaging against opposite sides of said rails for preventing tilting of said members in a vertical longitudinal plane relative to said rails, substantially as described.

22. Apparatus of the class described comprising a trough; means for cooling the contents of said trough; means for removing the contents of said trough, said removing means comprising a plurality of scraper and carrier members movable in said trough longitudinally thereof; endless elements carrying said members; reinforcing guide rails for said members; and rollers adjustably mounted on said members engaging against opposite sides of said rails for preventing tilting of said members in a vertical longitudinal plane relative to said rails, substantially as described.

23. Apparatus of the class described comprising a trough; a second trough arranged substantially parallel with said first mentioned trough, said troughs communicating with each other at intervals along their lengths; and means for controlling the communication between said troughs, substantially as described.

24. Apparatus of the class described comprising a trough; a second trough arranged alongside of said first mentioned trough, bottom portions of said troughs communicating with each other at intervals; and means for controlling the communication between said troughs, substantially as described.

25. Apparatus of the class described comprising a trough; a second trough arranged substantially parallel with said first mentioned trough and separated therefrom by a common wall, said wall having openings adjacent its lower edge establishing communication between said troughs; and means for controlling the passage through said openings, substantially as described.

26. Apparatus of the class described comprising a trough; a second trough arranged substantially parallel with said first mentioned trough and separated therefrom by a common wall, said wall having openings adjacent its lower edge establishing communication between said troughs; and a slidably mounted perforated plate controlling said openings, substantially as described.

27. Apparatus of the class described comprising a trough; a second trough arranged substantially parallel with said first mentioned trough and separated therefrom by a common wall, said wall having a plurality

of openings adjacent its lower edge establishing communication between said troughs, said openings being arranged in sets, each of said sets consisting of a plurality of openings of graduated sizes; and adjustable means coöperating with each set of the openings to control the flow therethrough, substantially as described.

28. Apparatus of the class described comprising a trough; a second trough arranged parallel with said first mentioned trough and separated therefrom by a common wall, said wall having a plurality of openings adjacent its lower edge establishing communication between said troughs, said openings being arranged in sets, each of said sets consisting of a plurality of openings of graduated sizes; and a slidably mounted plate having an opening arranged for cooperation with each set of said wall openings for controlling the flow therethrough, substantially as described.

29. Apparatus of the class described comprising a trough, said trough having admission openings at one side thereof; means for cooling the contents of said trough; means for removing the contents of said trough after cooling, said removing means comprising a plurality of spaced scraper and conveying members movable in said trough longitudinally thereof, certain of said members being open at their front and bottom sides; and an obliquely disposed transverse blade positioned in each of said last mentioned members adapted for travel in close proximity with the bottom of the trough, the forward end of said blade being positioned adjacent the admission openings of said trough, substantially as described.

30. Apparatus of the class described comprising a trough, said trough having admission openings at one side; means for cooling the contents of said trough; means for removing the contents of said trough after cooling, said removing means comprising a plurality of spaced scraping and conveying members movable in said trough longitudinally thereof; and means for uniformly distributing the contents of said trough over the bottom thereof upon the operation of said scraping and conveying members, substantially as described.

31. Apparatus of the class described comprising a collecting trough; a second trough; a communication between said troughs; means for cooling the substance admitted to said second trough; a disintegrating device arranged below one end of said trough; means movable longitudinally of said second trough for loosening the contents thereof and conveying the same toward said end of said trough and depositing the same into said disintegrating device; a storage chamber; and an elevator for conveying the disintegrated substance acted upon

by said disintegrating device from the latter to said storage chamber, substantially as described.

32. Apparatus of the class described comprising a collecting reservoir; an elongated trough; a duct leading from said reservoir to said trough; a second trough arranged substantially coextensive therewith; a communication between said troughs; means for cooling the substance admitted to said second trough; a disintegrating device arranged below one end of said second trough; means movable longitudinally of said second trough for loosening the contents thereof

and conveying the same toward one end of 15 said trough and depositing the same into said disintegrating device; a storage chamber; and an elevator for conveying the disintegrated substance acted upon by said disintegrating device from the latter to said 20 storage chamber, substantially as described.

In testimony whereof I have signed my name to this specification in the presence of two subscribing witnesses.

LARS LARSON.
